UNITED STATES PATENT OFFICE.

JOHN CHESNEY, OF PAULSBORO, NEW JERSEY, ASSIGNOR TO E. I. DU PONT DE NEMOURS POWDER COMPANY, OF WILMINGTON, DELAWARE, A CORPORATION OF NEW JERSEY.

PAPER-SHELL MACHINE AND MANDREL FOR SAME.

1,271,132.

Specification of Letters Patent.

Patented July 2, 1918.

Application filed September 18, 1915. Serial No. 51,342.

To all whom it may concern:

Be it known that I, JOHN CHESNEY, of Paulsboro, in the county of Gloucester, and in the State of New Jersey, have invented a 5 certain new and useful Improvement in Paper-Shell Machines and Mandrels for Same, and do hereby declare that the following is a full, clear, and exact description thereof.

My invention relates to a machine de- 10 signed for making paper shells but it relates especially to a machine for producing paper shells adapted to contain explosives.

The object of my invention is to provide a machine of this character which is pro- 15 vided with a mandrel which may be used for making shells with very small diameter, although the same is also adapted for the production of shells of large diameter. Another object of my invention is to provide an 20 apparatus of this kind in which air pressure is used to release the shells from the holes in the mandrel provided for holding the paper on the mandrel through the action of a vacuum, applied through said holes.

25 A further object of my invention is to provide such an apparatus in which a number of the moving parts previously found necessary have been omitted.

Again, another object of my invention is 30 to provide a mandrel in which the paper shell may be readily released and removed merely by the action of air pressure and without the necessity of mechanically loos- 35 ening or starting the shell before its removal by air pressure.

While my invention is capable of embodiment in many different forms, for the pur- 40 pose of illustration I have shown only one form thereof in the accompanying drawings, in which—

Figure 1 is a plan view of an apparatus made in accordance with my invention;

Fig. 2 is a side elevation of the same;

Fig. 3 is an enlarged detail of the man- 45 drel and certain parts connected thereto, shown partly in section;

Fig. 4 is a still further enlarged detail of the same;

Fig. 5 is a vertical section of a valve de- 50 signed for admitting compressed air to the apparatus; and

Fig. 6 is a similar view of the valve de- 55 signed to apply a vacuum therein.

In the drawings I have shown a paper shell machine comprising a frame 1 having 60 bearings 2 and 3 to support a main driving shaft 4, having at its end tight and loose pulleys 5 and 6, to which power may be applied from any suitable source. On the shaft 4 there is a gear 7 which drives a small gear 65 8 on a shaft 9 carried in bearing brackets 10 and 11, supported on the frame 1. On the shaft 9 there is, furthermore, a large gear 12, which drives a small gear 13, located on a rotating mandrel 14, also supported in the bearing brackets 10 and 11. This 70 rotating mandrel 14 is comprised of a main body portion 15, having a central passageway 16, which communicates with a smaller passageway 17 in an extension 18, smaller in 75 diameter than the main body portion 15, and which has a row of holes 19 along one side and an outlet opening 20 at its end or head containing a ball valve 21 coöperating with a valve seat 22 in said opening 20. A plug 75 23, having a peripheral recess 24 and a central opening 25 is located in the end of the outlet opening 20 to retain the ball valve in place. The opposite end of the mandrel 14 is arranged to fit within a stationary cylinder 26 for applying air pressure and a 80 vacuum to the mandrel. This stationary cylinder 26 is connected at its side to a pipe 27 leading to a valve 28, normally pressed upwardly against its valve seat 29 by a 85 spring 30, and adapted to be moved away from its valve seat by a valve rod 31 carrying the same, which projects upwardly in proximity to the cam 32, located on the shaft 4. From the valve 28, a pipe 33 leads to a 90 vacuum cylinder 34, which may be provided with a vacuum in any suitable manner. In the end of the stationary cylinder 26 there is, furthermore, provided a pipe 35 which leads to a valve 36 normally pressed against 95 its seat 37 by spring 38, and adapted to be moved away from the same by a valve rod 39 which is arranged so as to be operated by a cam 40 located on the shaft 4. From the valve 36 a pipe 41 leads to a compressed air cylinder 42, which may be supplied with compressed air in any suitable manner. Ad- 100

adjacent to the mandrel 14 there is located a feeding table 43 for supplying the paper to the mandrel.

In the operation of the machine, assuming that the mandrel 14 is being rotated by the shaft 4, a sheet of paper is fed to the mandrel 14 from the table 43 at the time when the valve 28 is open, so that the application of the vacuum through the holes 19 in the mandrel will hold the sheet of paper on the same. The rotation of the mandrel gradually rolls up the sheet of paper thereon, until the desired thickness of the shell has been obtained. At this point, any suitable apparatus not shown will come into action so as to crimp or fold the outer edge of the paper extending beyond the end of the mandrel 14 so as to close the end of the paper tube and form a shell. When this has taken place, the cam 32 will move the valve 28 so as to disconnect the vacuum cylinder 34 from the mandrel 14 and, thereafter the shaft 4 will move the cam 40 so as to open the valve 36 and admit compressed air into the interior of the mandrel 14. The compressed air thus admitted into the mandrel will loosen the formed tube so as to release the same from the perforations 19, inasmuch as the compressed air passes out through said perforations 19 against the interior of the shell. At the same time, the compressed air will pass outwardly through the passage 20 in the end of the mandrel 14, so as to move the shell outwardly so as to finally remove the shell from the mandrel 14. The apparatus is now ready for the formation of the next shell.

While I have described my invention above in detail, I wish it to be understood that many changes may be made therein without departing from the spirit of my invention.

I claim:

1. A mandrel for paper shells having lateral apertures and a head stationary with regard to the mandrel, said head having an end aperture.

2. A mandrel for paper shells having lateral apertures and a head stationary with regard to the mandrel, said head having an end aperture provided with a check valve.

3. In combination, a mandrel for paper shells having lateral apertures, a head stationary with regard to the mandrel, said head having an end aperture, and means for alternately applying to the mandrel compressed air and a vacuum.

4. In combination, a mandrel for paper shells having lateral apertures, a head stationary with regard to the mandrel, said head having an end aperture provided with a check valve, and means for alternately applying to the mandrel compressed air and a vacuum.

5. In combination, a mandrel for paper shells having lateral apertures, a head sta-

tionary with regard to the mandrel, said head having an end aperture, and means for alternately applying to the mandrel compressed air and a vacuum, comprising a compressed air system and a vacuum system, both leading to the apertures in the mandrel. 70

6. In combination, a mandrel for paper shells having lateral apertures, a head stationary with regard to the mandrel, said head having an end aperture provided with a check valve, and means for alternately applying to the mandrel compressed air and a vacuum, comprising a compressed air system and a vacuum system, both leading to the apertures in the mandrel. 75 80

7. A mandrel for paper shells provided with lateral apertures, a head stationary with regard to the mandrel, said head having an end aperture, means to release the shell from said lateral apertures by applying pressure through the same, and to remove the shell by applying pressure through the aperture in the head of the mandrel. 85

8. In combination, a mandrel for paper shells having lateral apertures, a head stationary with regard to the mandrel, said head having an aperture, and a stationary cylinder connected to the mandrel having valve controlled connections for alternately applying to the mandrel compressed air and 90 a vacuum. 95

9. In combination, a mandrel for paper shells having lateral apertures, a head stationary with regard to the mandrel, said head having an end aperture provided with a check valve, and a stationary cylinder connected to the mandrel having valve controlled connections for alternately applying to the mandrel compressed air and a vacuum. 100

10. In combination, a mandrel for paper shells having lateral apertures, a head stationary with regard to the mandrel, said head having an end aperture, a stationary cylinder connected to the mandrel having valve controlled connections for alternately applying to the mandrel compressed air and a vacuum comprising a compressed air system and a vacuum system, both leading to the apertures in the mandrel. 105 110

11. In combination, a mandrel for paper shells having lateral apertures, a head stationary with regard to the mandrel, said head having an end aperture provided with a check valve, and a stationary cylinder connected to the mandrel having valve controlled connections for alternately applying to the mandrel compressed air and a vacuum, comprising a compressed air system and a vacuum system both leading to the apertures in the mandrel. 115 120

12. A hollow mandrel for paper shells, having lateral apertures, and a check valve adjacent its head portion. 125

13. A hollow mandrel having lateral apertures and an end opening, and means re- 130

sponsive to the pressure within the mandrel for opening and closing said end opening.

14. A hollow mandrel for paper shells having apertures and means responsive to pressure upon the interior surface of the said mandrel for applying such pressure to move a shell relative to the mandrel.

In testimony that I claim the foregoing I have hereunto set my hand.

JOHN CHESNEY.
